CHANGE FORM CYLINDER MOUNTING FOR
ROTARY PRINTING PRESSESWilliam K. Eckhard, Westerly, R. I., assignor to
C. B. Cottrell & Sons Company, Westerly, R. I.,
a corporation of Delaware

Application May 24, 1935, Serial No. 23,193

14 Claims. (Cl. 101—247)

This invention consists in novel means for so mounting change form cylinders of a selected diameter that the cylinders may be readily moved into and out of printing coaction with their impression cylinder and may also be easily removed from the press frame when so desired.

This invention comprises a change form cylinder mounting for each end of the cylinder shaft box, in which mounting the cylinder shaft box 10 is slidably mounted in an open end pocket in the side frame and is removably connected to a manually operated eccentric stud, which stud in turn is mounted in a rotatively adjustable eccentric bushing.

15 A practical embodiment of this invention is represented in the accompanying drawing, in which

Fig. 1 represents a detail top plan view, partly in section, of one of the cylinder mountings and 20 the adjacent ends of the change form and impression cylinders;

Fig. 2 represents a detail side view of the same;

Fig. 3 represents a horizontal section taken in the plane of the line III—III of Fig. 2, looking 25 in the direction of the arrows; and

Fig. 4 represents a side view of a cylinder shaft box with a short shank for mounting a change form cylinder one-half of the diameter of the cylinder illustrated in full lines in Figs. 1 and 2.

30 The side frame of the rotary printing press is denoted by 1, the impression cylinder by 2, the change form cylinder by 3 and its shaft by 4.

It will be understood that similar mountings are provided for both ends of the change form 35 cylinder shaft, one mounting only being illustrated in the accompanying drawing, which mounting will now be described.

The side frame 1 has an open end pocket 5, the side walls of which form a track for slidably 40 mounting the change form cylinder shaft box 6, which box has an inwardly extended shank 7 which varies in length according to the diameter of its change form cylinder.

An eccentric stud 8 is removably connected 45 through the rods 9 and 10 to the shaft box shank 7 on both sides of the side frame 1 by a locking pin 11 which passes through the shank 7 and through the outer ends of the connecting rods 9 and 10. A cotter 12 may be employed for removably securing the locking pin 11 in its operative 50 position.

55 A handle 13 is provided for rocking the eccentric stud 8 to move the shaft box 6 inwardly and outwardly for bringing the change form cylinder 3 into and out of its printing contact with the im-

pression cylinder 2. An overthrow spring 14 may be provided for yieldingly holding the handle in either of its two diametrically opposed positions, a stop 15 on the side frame 1 serving to limit the inward throw of the handle. This handle 13 is 5 fast on the eccentric stud 8.

Means are provided for adjustably limiting the inward movement of the box 6 and thereby the change form cylinder, which means is herein shown as a screw 16 entering the bottom of the 10 open end pocket 5, the head of which screw is engaged by the inner end of the cylinder box shank 7 as the form cylinder 3 reaches its proper printing contact with the impression cylinder 2.

The manually operated eccentric stud 8 is 15 mounted in a rotatively adjustable eccentric bushing 17, which bushing is provided with an arm 18 having a concentric elongated slot 19, through which the shank of a set screw 20 passes into the side frame 1. This eccentric bushing 20 may be adjusted to take up any looseness in the connections between the rods 9 and 10, the eccentric stud 8 and the locking pin 11.

Pins 21, 22 project from the outer and inner faces of the side frame 1 in position to support 25 the connecting rods 9 and 10 when they are uncoupled from the shaft box and to hold the rods in position to facilitate their coupling and uncoupling.

In operation: A change form cylinder of the 30 selected diameter and its shaft boxes are placed in the frame and each of the boxes is coupled to the outer ends of its connecting rods 9 and 10 by the locking pin 11. Each handle 13 is then 35 swung over from its outward position shown in dotted lines in Fig. 2 to its inward position shown in full lines in the same figure. This movement of the handle will bring the form cylinder inwardly into its operative position in printing coaction with the impression cylinder 2. To throw 40 off the impression each handle 13 is swung back to its original position. This will move the change form cylinder away from the impression cylinder and at the same time will take off the tension on the locking pin 11 and thus permit 45 the pin to be easily withdrawn for the removal and replacement of the change form cylinder.

It will be noted that the inward movement of the change form cylinder is limited by the adjustable stop screw 16 and that, as has been above 50 described, all lost motion can be taken up by the rotatively adjustable eccentric bushing 17.

It is evident that various changes may be resorted to in the construction, form and arrangement of the several parts without departing from 55

the spirit and scope of my invention, and hence I do not intend to be limited to the particular embodiment herein shown and described, but

What I claim is:

- 5 1. A change form cylinder mounting comprising a side frame, a cylinder shaft box slidable therein, an eccentric stud mounted to rock in the side frame, means connecting the stud to said box, and manually operated means for rocking 10 the stud to move the cylinder into and out of its operative position.
- 15 2. A change form cylinder mounting comprising a side frame, a cylinder shaft box slidable therein, an eccentric stud mounted to rock in the side frame, means connecting the stud to said box, manually operated means for rocking the stud to move the cylinder into and out of its operative position, and means for adjustably limiting the inward movement of the cylinder box. 20
- 20 3. A change form cylinder mounting comprising a side frame having an open end pocket, a cylinder shaft box slidable therein, an eccentric stud removably connected to said box to permit the ready removal of the box and cylinder, and manually operated means for rocking the stud to move the cylinder into and out of its operative position. 25
- 30 4. A change form cylinder mounting comprising a side frame having an open end pocket, a cylinder shaft box slidable therein, an eccentric stud removably connected to said box to permit the ready removal of the box and cylinder, manually operated means for rocking the stud to move the cylinder into and out of its operative position, and means for adjustably limiting the inward movement of the cylinder box. 35
- 40 5. A change form cylinder mounting comprising a side frame, a cylinder shaft box slidable therein, an eccentric bushing mounted for rotative adjustment in the side frame, an eccentric stud mounted to rock in said bushing, means connecting the stud to said box, and manually operated means for rocking the stud to move the cylinder into and out of its operative position. 45
- 45 6. A change form cylinder mounting comprising a side frame, a cylinder shaft box slidable therein, an eccentric bushing mounted for rotative adjustment in the side frame, an eccentric stud mounted to rock in said bushing, means connecting the stud to said box, manually operated means for rocking the stud to move the cylinder into and out of its operative position, and means for adjustably limiting the inward movement of the cylinder box. 50
- 55 7. A change form cylinder mounting comprising a side frame having an open end pocket, a cylinder shaft box slidable therein, a rotatively adjustable eccentric bushing, an eccentric stud mounted therein and removably connected to said box to permit the ready removal of the box and cylinder, and manually operated means for rocking the stud to move the cylinder into and out of its operative position. 60
- 65 8. A change form cylinder mounting comprising a side frame having an open end pocket, a cylinder shaft box slidable therein, a rotatively adjustable eccentric bushing, an eccentric stud mounted therein and removably connected to said

box to permit the ready removal of the box and cylinder, manually operated means for rocking the stud to move the cylinder into and out of its operative position, and means for adjustably limiting the inward movement of the cylinder box. 5

9. A change form cylinder mounting comprising a side frame, a cylinder shaft box slidable therein and having a shank of a predetermined length according to the diameter of the change form cylinder, an eccentric stud connected to said box shank, and manually operated means for rocking the stud to move the cylinder into and out of its operative position. 10

10. A change form cylinder mounting comprising a side frame, a cylinder shaft box slidable 15 therein and having a shank of a predetermined length according to the diameter of the change form cylinder, an eccentric stud connected to said box shank, manually operated means for rocking the stud to move the cylinder into and out of its operative position, and means for adjustably limiting the inward movement of the cylinder box. 20

11. A change form cylinder mounting comprising a side frame having an open end pocket, a cylinder shaft box slidable therein and having a shank of a predetermined length according to the diameter of the change form cylinder, a rotatively adjustable eccentric bushing, an eccentric stud mounted in said bushing and removably connected to said box shank to permit the ready 30 removal of the box and cylinder, and manually operated means for rocking the stud to move the cylinder into and out of its operative position. 25

12. A change form cylinder mounting comprising a side frame having an open end pocket, a cylinder shaft box slidable therein and having a shank of a predetermined length according to the diameter of the change form cylinder, a rotatively adjustable eccentric bushing, an eccentric stud mounted in said bushing and removably 40 connected to said box shank to permit the ready removal of the box and cylinder, manually operated means for rocking the stud to move the cylinder into and out of its operative position, and means for adjustably limiting the inward movement of the cylinder box. 45

13. A change form cylinder mounting comprising a side frame, a cylinder shaft box slidable therein and having a shank of a predetermined length according to the diameter of the change 50 form cylinder, an eccentric stud, rods removably connecting the eccentric stud to said box shank upon both sides of the side frame, and a handle for rocking the stud to move the cylinder into and out of its operative position. 55

14. A change form cylinder mounting comprising a side frame having an open end pocket, a cylinder shaft box slidable therein and having a shank of a predetermined length according to the diameter of the change form cylinder, an eccentric stud, rods removably connecting the eccentric stud to said box shank upon both sides of the side frame, a handle for rocking the stud to move the cylinder into and out of its operative position, and an adjustable stop for limiting the 60 inward movement of the cylinder box. 65
